LOUIS E. CURDES, OF NAPOLEON, OHIO

SAFETY-RAZOR

Application filed January 15, 1930. Serial No. 420,930.

This invention relates to a safety razor.

The principal object of the invention is the provision of a safety razor embodying improved features of construction to the end that either a flexible or nonflexible blade may be used, and also so that the cutting edges of the blade may be disposed at different distances from the guard to suit the different requirements of the user.

10 The nature of the invention and its distinguishing features and advantages will appear when the following specification is read in connection with the accompanying drawings, in which

15 Figure 1 is a top view of a safety razor constructed in accordance with the invention;

Figure 2 is a section taken on the line 2—2 of Figure 1;

20 Figure 3 is a view similar to Figure 2 but showing the lower clamping member in a reversed position in order to obtain a changed adjustment of the cutting edges of the blade with respect to the lower clamping member, which constitutes the guard for the blade;

25 Figure 4 is a view of the under side of the top clamping member;

Figure 5 is a plan view of a flexible blade used with the razor;

30 Figure 6 is a view looking at the top side of the lower clamping member or guard;

Figure 7 is a view looking at the under side of a lower clamping member or guard;

Figure 8 is a plan view of a non-flexible blade adapted to be used with the razor.

Referring more particularly to the drawings, it will be apparent that the razor of the present invention comprises an upper clamping member 10, a lower clamping member 11 which co-operates with the clamping member 10, a blade 12 which is held in place between the clamping members 10 and 11, and a handle 13 adapted to be engaged with portions of the clamping members 10 and 11 to hold them in clamping engagement with the blade 12.

More specifically stated, the parts of the razor consist of the following features. The upper clamping member 10 is of quadrangular shape and is concavo-convex in cross section. Arranged centrally of the clamping

member 10 on the under concave face thereof and formed integral therewith is a stud or peg 14. This stud or peg 14 is angular in cross section, the same being square in the present instance with slightly rounded corners. The stud or peg 14 has a reduced cross sectional round end or extremity 15 which is threaded. The clamping member 11 is also quadrangular in shape and is somewhat larger in area than the clamping member 10. 55 The clamping member 11 is concavo-convex in cross section, and is provided with guard teeth 16 on the marginal edges thereof. It will therefore be understood that the clamping member 11 serves as a guard for the blade 12. The clamping member 11 has arranged centrally thereof on the upper concave face a rest or boss 17, of angular formation in plan, the same being square in the present instance. The clamping member 11 has a recess 18 in the lower convex face thereof. 60

65 The clamping member 11 also has a central hole or opening 19, of a shape to conform to the cross sectional shape of the stud or peg 14. The handle 13 is made of two parts in the present instance, and the upper end thereof is of such formation as to conform to the shape of the recess 18 in the clamping member 11. The upper end of the handle 13 also has a recess 20 therein and a threaded bore 21 70 disposed axially thereof.

75 It is to be understood that use may be made of a flexible blade or a non-flexible blade. In the present instance the blade 12 shown is a flexible one. This blade has narrow notches 80 or slits 22 extending diagonally in order to give to the blade the desired flexibility. The blade has a hole or opening 23 centrally thereof of a formation to conform to the shape of and to receive the stud or peg 14. 85

90 From the foregoing it will be apparent that the clamping members 10 and 11 may be brought together with the blade 12 disposed between the concave face of the clamping member 10 and the convex face of the 95 clamping member 11. The stud 14 projects through the holes 19 and 23, respectively, in the clamping member 11 and the blade 12. The handle 13 is applied to the clamping members 10 and 11 to maintain them in 100

clamping engagement with the blade 12, and is accomplished by threading the end of the handle having the bore 21 on the threaded end or extremity 15 of the stud 14, as shown in Figure 2. The blade 12 will be flexed so that the cutting edges thereof will be disposed relatively to the guard teeth 16 of the clamping member 11, for the purpose of giving a fine shave. On reference to Figure 2, it will be apparent that the stud 14 in part will be received in the recess 20 in the handle, and the end of the handle having this recess will be in contact with the rest or boss 17 of the clamping member 11, when the parts are assembled for use.

On reference to Figure 3, it will be apparent that the clamping member 11 may be reversed, in which case the blade 12 will be in contact with the rest or boss 17, and the upper end of the handle will be disposed in the recess 18 in contact with the clamping member 11. In this manner the clamping members 10 and 11 will be held in clamping engagement with the blade 12 which will not be flexed but will be gripped along the marginal edges thereof in a substantially flat condition, thereby disposing the cutting edges of the blade in a changed relation with respect to the guard teeth 16, for the purpose of giving more pronounced cutting edges to suit a particular requirement of the user, as distinguished from the greater angular disposition of the cutting edges shown in Figure 2 for a fine shave.

It will be apparent that the razor is adapted to present eight edges, four of one angularity and four of another angularity.

40 In Figure 8 there is shown a non-flexible blade 24 of quadrangular shape which presents four cutting edges. The blade 24 is rounded at the four corners and has the usual centering hole.

What is claimed is:

45 1. In a safety razor, the combination of co-operative upper and lower blade clamping members, the upper member having a lower concaved face, and the lower member having an upper convexed face, said lower member being associable with the upper member so that the concaved face of the latter will oppose the convexed face of the former, for the purpose of clamping therebetween a flexible blade in a flexed condition to vary the angular dispositions of the cutting edges of the blade

50 55 in relation to the edges of the clamping members when they are associated in the stated manner, and said lower member also being associable with the upper member so that the concaved face of the former will oppose the concaved face of the latter, said clamping members having co-operative means adapted for the purpose of clamping therebetween an inflexible blade, to obtain a different angular disposition of the cutting edges of the blade

60 65 in relation to the edges of the clamping mem-

bers when they are associated in the last stated manner.

2. In a safety razor, the combination of co-operative upper and lower blade clamping members, the upper member having a lower concaved face, and the lower member having an upper convexed face, said lower member being associable with the upper member so that the concaved face of the latter will oppose the convexed face of the former, for the purpose of clamping therebetween a flexible blade in a flexed condition to vary the angular dispositions of the cutting edges of the blade in relation to the edges of the clamping members when they are associated in the stated manner, and said lower member also being associable with the upper member so that the concaved face of the former will oppose the concaved face of the latter, said clamping members having co-operative means adapted for the purpose of clamping therebetween an inflexible blade, to obtain a different angular disposition of the cutting edges of the blade in relation to the edges of the clamping members when they are associated in the last stated manner, a handle, and engaging means on the handle and said clamping members to retain the latter in clamping engagement with the blade.

3. In a safety razor, the combination of co-operative blade clamping members consisting of an upper member and a separate lower member having guard portions on the edges thereof, each of said clamping members being concavo-convex in cross section, said lower clamping member having a blade rest portion on its concaved face, a peg projecting from the concaved face of the upper clamping member, said lower clamping member being adapted to be arranged on said peg with its convexed face opposing the concaved face of the upper clamping member to co-operate with the upper clamping member, for the purpose of clamping a flexible blade therebetween in a flexed condition to vary the angular dispositions of the cutting edges of the blade with respect to said guard portions, and said lever clamping member also being adapted to be arranged on said peg with its concaved face opposing the concaved face of the upper clamping member to co-operate with the latter for the purpose of clamping an inflexible blade therebetween to obtain a different angular disposition of the cutting edges of the blade with respect to said guard portions, a handle, and engaging means on said peg and handle to retain the clamping members in clamping engagement with the blade.

LOUIS E. CURDES.
